UNITED STATES PATENT OFFICE.

HENRY R. HELLER, OF NEW YORK, N. Y., ASSIGNOR, BY MESNE ASSIGNMENTS, TO
AUTO PNEUMATIC ACTION CO., A CORPORATION OF NEW YORK.

PLAYER-PIANO ACTION.

1,393,123.

Specification of Letters Patent.

Patented Oct. 11, 1921.

Application filed October 23, 1919. Serial No. 332,637.

To all whom it may concern:

Be it known that I, HENRY R. HELLER, a citizen of the United States, residing at New York city, in the county of Bronx and State 5 of New York, have invented certain new and useful Improvements in Player-Piano Actions, of which the following is a specification, reference being had therein to the accompanying drawing.

- 10 My invention relates to improvements in piano actions and more particularly has reference to means in combination therewith for adapting the same for use in combination with a player action adapted to be installed within the case of a piano. Various 15 other methods have been heretofore employed to this end. In the Danquard Patent 766,601, the player pneumatics are provided with a striker and plunger which lift the 20 wippen. In the Brown Patent 581,390, a lug is glued to the abstract of the piano action and this lug is forked at the base so as to permit a plunger attached to the movable part of the player pneumatic to engage 25 therewith to lift the abstract, but this is open to the objection that in placing the player action within the case it is necessary to use great care in order to see that each of the abstract lugs are properly engaged by 30 the connections with the movable parts of the player pneumatics and in the first mentioned patent it is necessary to provide plungers for the movable part of each of the player pneumatics and these must be properly guided in order to properly operate 35 upon the wippen. These objections are entirely overcome in my present construction as well as numerous other objections to be pointed out in various other previous arrangements of the player pneumatics in reference to the piano action.

40 In the accompanying drawings I have illustrated in Figure 1 a vertical transverse section of the upper part of a player piano, showing an embodiment of my invention, parts being in dotted outline and parts being broken away. Fig. 2 is an enlarged detail of the bracket or lug attached to the abstract of the piano action.

45 50 55 3 indicates the abstract of the piano action and according to a preferred embodiment of my invention I secure thereto a suitable lug or bracket 4 illustrated to better advantage in Fig. 2. This lug is a small piece of wood rectangular in cross-section with a kerf or

slot 5 drilled longitudinally to allow for the passage of the eye-screw 6 by which the lug 4 is attached to the abstract 3. 7 indicates another eye-screw adapted to penetrate the lug or bracket at right angles to the eye-screw 6 as shown, and may be provided at the lower end with the button 8 so that by rotating the lug or bracket 4 clockwise it is securely screwed into the abstract 3, and the eye-screw 7 may be rotated to adjust the projection of the button 8. This is the button that projects in the path of the movable portion 9 of the pneumatic so that when the pneumatic is collapsed, it lifts the abstract 3 through the medium of the lug or bracket 60 65 70 75 80 85 90 95 100 110

slot 5 drilled longitudinally to allow for the passage of the eye-screw 6 by which the lug 4 is attached to the abstract 3. 7 indicates another eye-screw adapted to penetrate the lug or bracket at right angles to the eye-screw 6 as shown, and may be provided at the lower end with the button 8 so that by rotating the lug or bracket 4 clockwise it is securely screwed into the abstract 3, and the eye-screw 7 may be rotated to adjust the projection of the button 8. This is the button that projects in the path of the movable portion 9 of the pneumatic so that when the pneumatic is collapsed, it lifts the abstract 3 through the medium of the lug or bracket 60 65 70 75 80 85 90 95 100 105 110

qualities produced by striking with this arrangement of the action is superior to the results obtained by other arrangements.

Of course it will be understood that various modifications may be made in the construction and arrangement of parts without departing from the spirit of the invention as claimed.

I claim:

- 10 In a player piano having a self-contained piano and player action, projections and stops upon the abstracts of said piano action and projections from the pneumatics of said player action adapted to travel in the path
15 of said first mentioned projections for oper-

ating said piano action directly and pneumatically, each of said abstract projections having a longitudinal passage for a screw adapted to secure the same to said abstract and a transverse passage for another screw adapted to penetrate said first mentioned screw and for regulating the position of the stop of said projection with reference to said pneumatic projection.

In testimony whereof I hereunto affix my 25 signature in the presence of two witnesses.

HENRY R. HELLER.

Witnesses:

W. G. HELLER,
VINCENT BISULK.
